[57] CLAIM

The ornamental design for an imitation tuxedo garment, as shown and described.

DESCRIPTION

FIG. 1 is a front elevational view of an imitation tuxedo garment showing my new design, with a top portion thereof mated with a bottom portion thereof;

FIG. 2 is a front elevational view thereof with the top portion separated from the bottom portion;

FIG. 3 is a side elevational view thereof with the top portion separated from the bottom portion;

FIG. 4 is a rear elevational view thereof with the top portion separated from the bottom portion; and,

FIG. 5 is a side elevational view showing the opposite side of the imitation tuxedo garment shown in FIG. 3.
